UNITED STATES PATENT OFFICE.

LYNUS CLYDE REYNOLDS, OF WASHINGTON, DISTRICT OF COLUMBIA.

CARD-INDEX.

1,047,840.

Specification of Letters Patent. Patented Dec. 17, 1912.

Application filed December 7, 1911. Serial No. 664,359.

To all whom it may concern:

Be it known that I, LYNUS C. REYNOLDS, a citizen of the United States, and a resident of Washington, in the District of Columbia, have invented an Improvement in 5 Card-Indexes, of which the following is a specification.

My invention is an improvement in that class of card indexes in which a series of 10 cards having names or other matter printed thereon, in alphabetical order, are held detachably in a frame one above another, and in such manner that the printed matter is always visible on the faces of the cards, 15 each of which is provided with some form of device adapted to engage and support the one above it.

I have simplified, reduced the cost, and improved the efficiency of the card-supporting device and have also improved the construction of the card-holding frame, as hereinafter described and illustrated in the accompanying drawings, in which—

Figure 1 is a perspective view of the 25 index composed of a series of cards and the frame in which they are held and supported. Fig. 2 is a perspective view of the frame alone. Fig. 3 is a rear or back view of a portion or section of the index illustrating 30 the arrangement of the card tongues, whereby each card is supported on another below it. Fig. 4 is a perspective view illustrating the manner of inserting a card in the frame. Fig. 5 is a perspective view 35 illustrating the lifting of a card in rear of one just inserted. Fig. 6 is a back view showing a card raised for readjustment after one has been inserted. Fig. 7 is a vertical section of cards duly adjusted and supported by each other in the frame.

The frame of my improved index has an oblong rectangular form and is distinguished by the utmost simplicity of construction, it being composed of interiorly 45 grooved side bars 1 and top and bottom cross bars 2 and 3, all formed of thin sheet metal such as tinned iron or aluminum. As shown in Figs. 1 and 2, the flat top cross-bar 2 is soldered or riveted to the 50 backs of the side bars 1, so that the grooves of the latter are left open or free at the top to permit cards to be slid out of the frame. The bar 2 has a downwardly and rearwardly projecting flange 2^a which serves as 55 a guide for the cards in that it prevents the tongues of the latter catching on the

bar when cards are slid out of the frame. The bottom cross-bar 3 has an angle form in cross section and is so applied to the ends of the side bars as to practically close 60 the frame at that point, so that it forms a direct support for the bottom card of a series and thus indirectly for the whole series, while preventing their escape downward. By constructing the frame as described, it has due rigidity, also extreme 65 lightness, and may be manufactured at very small cost, while at the same time adapted to hold cards securely and permit their ready insertion and removal.

The cards, indicated by the numeral 4—see especially Figs. 4 and 6—have an oblong rectangular form and are provided with tongues 5 which are integral portions of the cards, the same being formed by an inverted 70 U-shaped cut and by bending backward or outward the tongues thus formed, so that they project at a sharp angle and are thereby adapted to engage the bottom of the card above and thus support the latter.

Fig. 1 shows a face view of the frame nearly filled with cards, and all of those above the bottom one supported on the latter. In other words, each card in the series above the bottom one is supported on the one 85 below it, its lower edge resting on the tongues 5 of the lowest or bottom card of the series. The arrangement of the cards with reference to the supporting tongues is best 90 illustrated in Figs. 3, 6 and 7.

In order to insert a card in the frame between any that may be already in it, one hand suffices, and it is only necessary to bow the card slightly outward, as in Fig. 4, to 95 permit insertion of its ends simultaneously or successively in the grooves of the side bars 1, and then, the card being released, it may be pushed into place, so that its lower edge rests on the projecting tongues 5 of the card below it. In such case, however, the inserted card lies directly in front of another, and it is therefore necessary to raise the rear one and with it all that lie above and are supported upon its tongues. In this operation, as shown in Fig. 5, the card behind the 100 newly inserted one is seized between thumb and finger and lifted to the position shown in Fig. 6, and in such case all the cards above it are necessarily raised also, since each rests on the tongues of the next card below it. 110 Practically this operation is reversed for removal of a particular card. Thus, the card

to be removed is seized and drawn upward until its lower edge is above or free of the card that was in front of and below it, and this, of course, raises also all the cards that lie above the particular card which is being removed; then, upon bowing the latter, its ends are drawn out of the grooves of the side bars 1, and its tongues are at the same time sprung outward sufficiently to free them 10 from the bottom edge of the card above.

In the construction of the cards, they may be cut out of large sheets by means of a cutter also constructed to serve as a die in that it presses the tongues outward simultaneously with the cutting operation, so that under ordinary conditions they retain the spring or cant thus given and stand permanently at the required acute angle. Thus by this construction, the cards themselves are 20 provided with integral spring supports for those above them in the frame.

It will be seen that while the angular lower cross-bar 3 supports the lower card and thus the entire series above it and prevents 25 the escape of the cards at that point, the arrangement of the top bar 2 permits them to be all slid bodily out of the frame when desired. It also permits the convenient insertion of all or a series of cards, so that they

do not require to be bent or bowed for the 30 purpose.

What I claim is:—

1. The improved card-index comprising a frame having parallel, interiorly grooved, side bars, a series of elastic cards adapted to 35 slide in said bars, each having two integral spring tongues arranged parallel to the bottom edge and projecting backward and upward at a slight angle, each card overlapping and resting on the tongues of the one 40 next below, while its own tongues support the cards above it, by means of which arrangement insertion of additional cards can be readily accomplished, as shown and described. 45

2. The card-index frame, comprising parallel interiorly grooved side-bars, a connecting top-bar secured on the backs of said side-bars and having a downwardly and outwardly projecting flange, in combination 50 with cards adapted to slide in the side-bars and having upwardly and rearwardly projecting tongues, as shown and described.
